US00D872641S

(12) **United States Design Patent** (10) **Patent No.:** **US D872,641 S**
(45) **Date of Patent:** **** Jan. 14, 2020**

(54) **SCULPTURE**

(71) Applicant: **Samsung Electronics Co., Ltd.**, Suwon-si (KR)

EM 00268115-0017 4/2005

(72) Inventors: **Pilkwon Jung**, Changwon-si (KR); **Kyubok Lee**, Seoul (KR)

(73) Assignee: **SAMSUNG ELECTRONICS CO., LTD.**, Suwon-si (KR)

(**) Term: **15 Years**

(21) Appl. No.: **29/608,750**

(22) Filed: **Jun. 26, 2017**

(30) **Foreign Application Priority Data**

Dec. 29, 2016 (KR) 30-2016-0064188

(51) **LOC (12) Cl.** **11-02**
(52) **U.S. Cl.** USPC **D11/157**

(58) **Field of Classification Search**

USPC D11/204, 217, 223, 32, 238, 14, 30, 44, D11/48, 61, 81, 95, 99, 116, 125, 131, D11/133, 141, 149, 157, 184; D20/10, D20/11, 23, 29; D21/381, 483; D5/30; D6/674, 307; D14/490; D18/24-33; D19/34.3, 97, 59; D3/211, 270, 271.1; D10/6; 63/1.11, 20; 40/596; 434/82, 434/159-161, 171, 172, 167, 178

CPC . G09B 17/00; G09B 1/06; G09B 1/40; G09B 1/00

(57) **CLAIM**

The ornamental design for a sculpture, as shown and described.

DESCRIPTION

FIG. 1 is a front perspective view of a sculpture showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a cross-sectional view taken along the line 8-8 in FIG. 2; and,

FIG. 9 is a front perspective view thereof, shown in an example environment.

The dash-dash broken lines shown in FIG. 8 illustrate portions of the sculpture that form no part of the claimed design. The dot-dashed broken lines and associated stippled surface in FIG. 9 depict environmental subject matter that forms no part of the claimed design.

1 Claim, 8 Drawing Sheets
